TOY

Charles W. Lambert, Detroit, Mich.

Application October 12, 1938, Serial No. 234,714

6 Claims. (Cl. 280—9)

This invention relates to toys and has for an object to provide a toy which may be convertible into a sled or into a wheeled vehicle as desired.

A further object is to provide novel brackets for assembling a wheel and a sled runner perpendicular to each other and mounting the same to pivot about a horizontal axis so as to dispose either the wheel or the runner in contact with the ground.

10 A further object is to provide apparatus of this type which will be formed of a few strong simple and durable parts, which will be inexpensive to manufacture, and which will not easily get out of order.

15 With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

25 Figure 1 is a side elevation of a toy constructed in accordance with the invention drawn to reduced scale.

Figure 2 is a plan view of the toy shown in Figure 1.

30 Figure 3 is a detail cross sectional view taken on the line 3—3 of Figure 1 showing one of the front wheel and runner assemblies.

Figure 4 is a cross sectional view taken on the line 4—4 of Figure 3.

35 Figure 5 is a side elevation of the parts shown in Figure 3 but showing the runner in ground engaging position instead of the wheel.

Figure 6 is a cross sectional view taken on the line 6—6 of Figure 2 showing the rear runner and wheel assembly of the toy.

40 Figure 7 is a fragmentary detail view showing the runner of Figure 6 in ground engaging position and the wheels elevated.

Figure 8 is a front elevation of a modified form 45 of front wheel and runner assembly showing the steering knuckle and locking bar for locking the wheel in elevated position.

Figure 9 is a fragmentary detail view showing the runner of Figure 8 in ground engaging position.

50 Figure 10 is a detail cross sectional view showing a modified form of rear wheel and runner construction which is to be used in conjunction with the front wheel and runner construction shown in Figure 8.

Figure 11 is a fragmentary vertical sectional view of the parts shown in Figure 10 and showing the locking bolt for holding the wheel in ground engaging position.

Figure 12 is a detail perspective view of the 5 knee action bar which carries the springs for permitting rocking movement of the sled runner to ride over obstructions.

Figure 13 is another modified form of bracket for mounting a wheel and runner in unit assembly.

10 Figure 14 is a front elevation of one of the front wheel and runner assemblies of a four wheel toy instead of the three wheel toy shown in Figure 1.

15 Figure 15 is a front elevation similar to Figure 14 but showing the runner in ground contacting position.

Figure 16 is a front elevation of one of the rear wheel and runner assemblies showing the 20 runner in ground engaging position.

Figure 17 is a detail longitudinal sectional view showing one of the axles reinforced at the end with a metallic cup.

25 Referring now to the drawings in which like characters of reference designate similar parts in the various views, 10 designates the body of the toy and the same may be of any shape desired, in the present embodiment being shown as a flat board provided with lateral wings 11. 30 Longitudinal braces 12 are disposed upon the bottom face of the body and transverse braces 13 are disposed upon the bottom of the longitudinal braces. A front axle 14 is rigidly secured to one of the transverse braces 13 for 35 carrying the dirigible front wheel and runner assemblies, as best shown in Figure 3, and a longitudinally extending bar 15 is secured to the transverse braces and to the body 10 and carries the single rear wheel and sled runner assembly, 40 as best shown in Figure 6.

Referring to Figures 3, 4 and 5 each front wheel and sled runner assembly comprises a bracket 16 which is provided at the upper end with spaced arms 17 which are secured to a 45 plate 18, of the general shape shown in Figure 12, through the medium of bolts 19. The plate is provided with hinge ears 20 between which hinge ears 21 carried by a runner 22, are interposed. A pivot pin 23 is passed through the 50 ears 20 and 21. As best shown in Figure 5 helical springs 24 are interposed between the ends of the plate 18 and the sled runner to permit the sled runner yielding on the pivot pin 23 to pass over obstructions.

A shaft 25 is journaled in a bearing 26 formed on the lower end of the bracket and is equipped with a ground wheel 27. The ground wheel 27 extends perpendicular to the sled runner 22.

- 5 As best shown in Figures 3, 4 and 5 the bracket is provided with a pair of hinge ears 28 which receive between them a hinge ear 29 carried by a plate 30, shown best in Figure 4, which is provided with steering knuckle ears 31 which receive 10 the axle 14 and is pivotally connected to the axle by a vertically disposed pivot pin 32.

A pivot pin 33 is passed through the hinge ears 28 of the bracket and through the hinge ear 29 of the plate 30 to pivotally mount the 15 wheel and runner assembly on the axle so that either the wheel or the runner may be swung into contact with the ground.

A steering arm 34 is formed integral with the lower ear 31 and is connected by a link 35 to 20 the column 36 of the handle bars 37, best shown in Figures 1 and 2.

For locking the runner in raised position the bracket 16 is provided with ears 38 which receive between them a lug 39 carried by the upper 25 steering knuckle ear 31. A bolt 40 is passed through the ears and the lug to lock the runner in released position underneath the respective wing 12 of the body.

For locking the wheel in raised position when 30 the runner is in use, a nut 41 is threaded on the shaft 38 of the ground wheel. The shaft is received in the bifurcated end of a locking arm 42 which is bolted to the lower steering knuckle ear 31, as shown at 43, when the ground wheel is 35 rocked to released position. The nut 41 may then be tightened to hold the ground wheel in released position.

As best shown in Figure 6, a pair of ground 40 wheels 44 are mounted on a short axle 45 which is journaled in the arms 46 of a bracket 47. The bracket is pivotally connected to swing on a horizontal pivot pin 48 carried by a pair of ears 49 which depend from a base plate 50 which is secured to the beforementioned bar 15 of the 45 body as shown at 51. The bracket 47 is provided on one side with a plate 52 to which is bolted a plate 53 similar to the plate shown in Figure 12 and having ears 54 to which the hinge ears 55 carried by a runner 56, are secured. Helical 50 springs 57 are mounted at the ends of the runner below the ends of the plate 53 to permit the runner to ride over obstructions. When the ground wheels 44 are in use the runner 56 is 55 raised to the horizontal. For locking the runner in this position a bolt 58 is passed through one of the ears of the plate 53 and through an opening in the beforementioned base plate 50.

When the runner is to be used the ground 60 wheels are swung up to the horizontal and locked in this position by interchanging the bolt 58 in an opening 59 in one of the branches 46 and in an opening 60 in the base plate 50.

Figures 8, 9, 10 and 11 illustrate a modified 65 form of the invention in which four wheel and runner assemblies are secured to respective front and rear axles 61 and 62 suspended from longitudinal braces 63 which depend from the body 64 of the toy.

The dirigible wheel and runner assembly is 70 shown in Figure 8 to comprise an inverted L-shaped bracket 65 which is pivotally connected by a pivot pin 66 to a hinge ear 67 which is formed integral with a steering knuckle 68 which is pivotally connected to a bracket 69 on 75 the end of the axle 61 by a pivot pin 70.

A ground wheel 71 is provided with a shaft 72 which is journaled in a bearing 73 on the end of the long arm of the bracket 65.

For locking the ground wheel in operative position, the bracket is provided with an ear 74. A 5 bolt 75 is passed through the ear and through the steering arm 76 of the steering knuckle to lock the wheel in contact with the ground and to lock the runner 77 in released position.

The runner is similar to the runner heretofore 10 described and is provided with hinge ears 78 which are connected by a pivot pin 79 to hinge ears 80 carried by a plate 81 which is fixed to the bracket 65. Springs 82 are interposed between the ears of the runner and the bracket 81 15 to permit the runner riding over obstructions.

The runner is locked in ground contacting position through the medium of a locking arm 83 which is secured to the pivot bolt 70 of the steering knuckle and is bifurcated at the end to receive the reduced end 84 of the shaft 72 of the ground wheel. A nut 85 is carried by the shaft and is tightened against the locking arm to hold the ground wheel elevated and to hold the runner in ground contacting position. 25

The rear wheel and runner assembly is shown in Figure 10 to comprise an inverted L-shaped bracket 86 similar to the bracket of the front dirigible wheel and runner assembly. The long arm of the bracket is equipped with a ground 30 engaging wheel 87. The short arm of the bracket is of channel construction as best shown in Figure 11. A pivot pin 88 is passed through the sides of the channel of the short arm and through an ear 89 which projects from a bracket 90 carried by the rear axle 62. A locking bolt 91 is passed through the web of the short arm of the bracket and into an opening in the bracket 90 to hold the ground wheel in contact with the ground and hold the runner 92 raised. 40

The runner 92 and its connection with the bracket 86 are the same as heretofore described, springs 93 being interposed between the ends of the runner and the ends of the plate 84 similar to the plate 18, shown in Figure 12, carried by 45 the long arm of the bracket 86. For holding the runner in ground engaging position, a locking arm 94 is bolted to the axle 62, as shown at 95 and is provided with a bifurcated free end to receive a reduced neck 96 on the shaft of the 50 ground wheel. A nut 97 on the shaft secures the ground wheel in raised position and secures the runner in ground contacting position. Another modified form of the invention is shown in Figures 14 to 17 inclusive. In this form of the 55 invention the dirigible front wheel and runner assembly shown in Figure 14, comprises a bracket 98 which is provided with an integral bearing 99 for the shaft of the ground wheel 100. The bracket is provided with steering knuckle ears 60 101 which receive the front axle 102 and through which a pivot pin 103 is passed. The steering arm 104 is bolted to the bracket.

The runner 105 is provided with springs 106 to permit the runner riding over obstructions 65 and the springs are interposed between the runner and the plate 107 which carries hinge ears 108. A pivot pin 109 is passed through these hinge ears and through the lower end of the bracket 98 to hingedly mount the runner to 70 swing in a vertical plane on the bracket.

For locking the runner in released position a locking arm 110 is connected to the steering knuckle bolt 103 and is secured to the runner by a bolt 111. 75

For locking the runner in ground contacting position, in which position the ground wheel 100 is raised vertically from the ground, an angle iron bracket 112 is secured to the steering knuckle bolt 103 and is bolted to the hinge ears 108 of the runner as shown at 113.

The rear wheel and runner assembly of this modified form of the invention is shown in Figure 16 to comprise a bracket 114 similar to the bracket 98 with the exception that the steering arm 104 is dispensed with and the ears 115 of the bracket are fixedly secured to the end of the axle 105 through the instrumentality of a bolt 116 and a screw 117. The runner 118 is pivotally mounted to swing in a vertical plane on a pivot pin 119 carried by the bracket 114. The runner is secured in ground contacting position through the medium of an angle iron bracket 120 which is secured to the bolt 116 and is bolted 20 to the hinge ear 121 of the bracket, as shown at 122.

As shown in Figure 17 the ends of the axles 123 may be provided with metal caps 124 to receive the steering knuckle bolts or other bolts. A simplified form of bracket 125 is shown in Figure 13, this form of bracket being provided at the lower end with a bearing 126 to receive the shaft of a ground wheel. The bracket is provided centrally with hinge ears 127 to receive 30 a pivot pin through which the unitary assembly of ground wheel and runner may be swung upon the pivot pin in a vertical plane as described in connection with the form of the invention shown in Figure 3. The upper end of the bracket is provided with ears 128 to receive the hinge ears 20 of the plate 18 for attaching the runner to the assembly.

From the above description it is thought that the construction and operation of the invention 40 will be fully understood without further explanation.

What is claimed is:

1. In a toy, a body, brackets connected to the body, a ground wheel and a sled runner carried by each bracket said ground wheel and said runner being perpendicular to each other, means mounting the bracket to swing upon a horizontal pivot to selectively present the ground wheel or runner to the ground, and means for locking the bracket to hold the ground wheel or the runner in ground contacting position.
2. In a toy, a body, a bracket pivotally connected to the body to swing about a horizontal pivot, a steering knuckle connection between the bracket and the body, a ground wheel and a sled runner carried by the bracket perpendicular to each other, an ear carried by said steering knuckle, an ear carried by the bracket, a lock-

ing bolt adapted to be engaged through both of said ears to hold the runner raised and to hold the wheel in ground contacting position, an arm projecting from said steering knuckle, and means carried by the bracket engageable with said arm to hold the wheel raised and to hold the runner in ground contacting position.

3. In a toy, a body, a bracket pivotally connected to the body to swing about a horizontal pivot, a plate carried by the bracket at one end thereof, a runner hinged to the plate, springs on opposite sides of the hinge of the runner engaging the runner and the plate to permit the runner to yield over obstructions, a shaft carried by the other end of the bracket, a ground wheel on the shaft, means for locking the runner raised and the ground wheel in engagement with the ground and means for locking the ground wheel raised and the runner in contact with the ground.

4. In a toy, a body, an axle on the front end of the body, steering knuckles on the ends of the axle, a bracket pivotally connected to swing upon a horizontal pivot on each steering knuckle, a ground wheel and a sled runner carried by each 25 bracket said ground wheel and said runner being perpendicular to each other, and means for supporting the rear end of the body.

5. In a toy, a body, means for supporting the front end of the body, and a combined sled runner and ground wheel assembly for supporting the rear end of the body, comprising a bracket adapted to be secured to the body, a ground wheel carried by the bracket, a sled runner carried by the bracket, means for mounting the 30 bracket to swing about a horizontal pivot on the body to selectively present either the ground wheel or the sled runner in engagement with the ground, and means for locking the ground wheel and the sled runner in operative position.

6. In a toy, a body, hinge ears on the body, a bracket having hinge ears engaged with the body hinge ears and having a web, a projection on the body between the body hinge ears, a bolt detachably engaged through said web and through said projection to hold the bracket at one limit of its pivotal movement, a ground wheel carried by one end of said bracket, a sled runner carried by the other end of said bracket and disposed at a right angle to said ground wheel a bifurcated arm carried by said body, a shaft for the ground wheel having a threaded end, said shaft being receivable in the arm, and a nut on said threaded end engageable with said arm for locking the bracket at its other limit of 45 pivotal movement.

CHARLES W. LAMBERT.
